COMBINED END TABLE AND DESK

Earl S. Prock, Chicago, Ill.

Application March 12, 1956, Serial No. 40,544

Term of patent 7 years

(Cl. D33—7)

FIG. 1

FIG. 2

FIG. 3

FIG. 4

Fig. 1 is a perspective view of a combined end table and desk embodying my new design;

Fig. 2 is a perspective view thereof taken from the opposite side and end from that shown in Fig. 1;

Fig. 3 is a perspective view of the combination as shown in Fig. 1 but illustrated in an open position; and

Fig. 4 is a perspective view of the combination as shown in Fig. 2 but illustrated in an open position.

I claim:

The ornamental design for a combined end table and desk, as shown.
